UNITED STATES PATENT OFFICE.

OTTO E. HOFFMAN, OF CHICAGO, ILLINOIS.

LEATHER-SEWING MACHINE.

1,119,017.

Specification of Letters Patent.

Patented Dec. 1, 1914.

Application filed October 24, 1913. Serial No. 796,995.

To all whom it may concern:

Be it known that I, OTTO E. HOFFMAN, a citizen of the United States, and resident of Chicago, county of Cook, and State of Illinois, have invented certain new and useful Improvements in Leather-Sewing Machines, of which the following is a specification, and which are illustrated in the accompanying drawings, forming a part thereof.

10 The invention relates to sewing machines, and more particularly to those intended for uniting by seams such heavy materials as leather and the like.

The object of the invention is to provide a machine of improved construction for sewing such articles as traveling and golf bags, and the invention contemplates a machine adapted for making seams at such parts of these devices as have heretofore been inaccessible for machine sewing.

In the accompanying drawings Figure 1 is a side elevation of a leather sewing machine embodying the improvements provided by the invention, one position of certain parts being indicated by dotted lines; Fig. 2 is a detail vertical sectional view of the work support and needle operating mechanism; Fig. 3 is a sectional view showing some of the parts illustrated in Fig. 2 from a different sectional plane; Fig. 4 is a detail plan view of the machine; Fig. 5 is a detail front elevation of the machine, some parts being shown in section; Fig. 6 is a detail front elevation showing a modified form of construction; and Fig. 7 is a detail sectional view taken on the line 7-7 of Fig. 3.

The machine illustrated in the drawings is of a form adapted to make a well known form of chain-stitch seam from a single thread, as A. As the invention contemplates the use of a work support of restricted dimensions, the mechanism shown is also of the so-called awl-feed type wherein the feeding of the work is accomplished by a lateral movement of the awl.

The parts of the machine are conveniently associated upon a frame, which is generally designated by the numeral 10. This frame preferably comprises the floor plate 11 and pedestal 12 having the overhanging top 13. When the operative parts of the machine are to be driven by power, a drive shaft 14 is preferably located at the top of the pedestal 12. As shown, this drive shaft extends through and is journaled in brackets, as 15,

which rise from the top of the pedestal. A belt pulley 16 and crank disk 17 are fixed upon opposite ends of the drive shaft 14. A sprocket wheel 18 is mounted on the 60 drive shaft 14 intermediate its ends.

One form of work support is generally designated by the numeral 19 in Figs. 1 and 2. A modified form of work support is shown at 20 in Fig. 6. Each of these work 65 supports preferably comprises an upright tubular standard 21, having a pointed tubular anvil block 28 fixed upon its higher end. Most desirably the tubular standard 21 is horizontally offset intermediate its ends, as 70 at 22 (Figs. 1 and 2) or at 23 (Fig. 6). To facilitate the application of the work to the work support, the standard 21 is pivotally secured to the floor plate 11 at a point some distance in front of the foot of the 75 pedestal 12. As shown, a pair of laterally separated pivot lugs 24, 25, rise from the floor plate 11, and the lower end of the standard 21 is bifurcated, its two arms, as 26, 27, being pivotally connected to the 80 pivot lugs 24, 25, respectively, as by bolts 25.

Any convenient means may be employed for securing the work support, 19 or 20, in the upright position of service. As shown, a spring bolt 63 (Fig. 6) plays through an 85 aperture 64 in one of the pivot lugs, as 25, for entering an aperture 65 in the corresponding arm, as 27, of the bifurcated lower end of the standard 21 to normally prevent the swinging of the standard away from the 90 said upright position. A pedal 66, pivotally secured to the floor plate at 67 and having a slotted opening 68 for receiving a stud 69 which projects laterally from the bolt 63 adjacent its outer end, serves for withdrawing the bolt. When the bolt is withdrawn the work support, as 19, may be swung forwardly to the position indicated by dotted 95 lines in Fig. 1 for receiving the work.

The usual hooked form of needle is shown 100 at 29. The awl is shown at 30. The needle 29 is carried by the tubular anvil block 28, and is reciprocated through an opening 31 at the pointed end of the same. The awl 30 engages the work from above the support, 105 its point entering the opening 31 at the higher end of the work support in front of the needle 29 when the needle is retracted. To permit rearward movement of the awl for advancing the work, the opening 31 is 110 slotted, as appears in Fig. 3.

The needle 29 is conveniently carried by

a slide 41, which is mounted within the bore of the tubular anvil block 28 and is actuated from the crank disk 17 on the drive shaft 14. As shown, the crank disk 17 carries a wrist pin 32, and a pitman 33 operatively connects this wrist pin with a lever 34 which is located near the floor plate 11 and extends between the pedestal 12 and work support 19 or 20. The lever 34 is pivotally supported intermediate its ends, as upon a bracket 35, which rises from the floor plate 11. The forward end of the lever 34 preferably extends into the space between the two arms, as 26, 27, of the bifurcated lower end of the standard 21. When the tubular standard is horizontally offset intermediate its ends, as at 22 (Fig. 2) or 23 (Fig. 6), a second lever 37 extends through the said horizontally offset portion of the same. As shown, this lever is pivotally supported intermediate its ends, as upon a pin 38 which extends through the horizontally offset portion 22 or 23 of the standard. A link 39, which is housed within the lower upright tubular portion of the standard 21, serves for connecting one end of the lever 37 with the forward end of the lever 34. In order that the connection of the link 39 with the lever 34 may not interfere with the swinging of the work support, as 19, to the position indicated by dotted lines in Fig. 1, the forward end of the lever is provided with a slot 36 for receiving the connecting pin, as 40. The opposite end of the lever 37 is connected with the needle slide 41. Usually the connection between the lever 37 and slide 41 will include a link, as 42 or 43, having its opposite ends pivotally attached to the slide 41 and lever 37, respectively.

A cast-off finger is shown at 44. This cast-off finger also operates through the opening 31 at the pointed end of the anvil block 28. It moves with the needle 29 during a part of the movement of the latter in each direction. A slide 45, which is mounted within the bore of the anvil block 28 alongside of the slide 41 (Fig. 7) serves for carrying the cast-off finger 44. A stud 46, fixed in the slide 45 and entering a slotted opening 47 in the slide 41, serves for actuating the cast-off finger 44 to cause it to move in unison with the needle 29 during a part of the movement of the latter in each direction. Preferably a friction element is provided for holding the slide 45 against movement during the initial movement of the slide 41 and needle 29 in each direction. This friction element is shown as taking the form of a disk 48, preferably made of leather, or other yielding material, and fitted within a suitable opening, as 49, in the wall of the anvil block 28 to bear against the slide 45. A spring finger 50, adjustably held against the outside of the anvil block 28 by a set-screw 51 (Fig. 3), bears against

the outer face of the disk 48 for pressing the same against the slide 45.

A head, generally designated 52, serves for carrying the operative parts of the machine which are located above the plane of the work. This head is desirably secured to the overhanging top 13 of the pedestal 12, as by screw-bolts 53. As shown, the head 52 takes the form of a plate having brackets, as 54, rising therefrom for supporting an operating shaft 55. It preferably also has a depending bracket 56 for slidably receiving the presser foot, as 57. A swinging bracket 58, pivotally secured to the head 52, as at 59 (Fig. 1), serves for carrying the awl 30 and the usual thread guide or looper 60. This bracket may also carry a spindle 61 for receiving a spool, as 62, from which the thread A is supplied. The oscillation of the awl 30 for feeding the work is accomplished by swinging the bracket 58.

The operating shaft 55 serves for actuating the awl 30, presser foot 57, and thread guide 60. To this end it is driven at uniform speed with the drive shaft 14, as by means of a sprocket chain 70 which turns over the sprocket wheel 18 on the drive shaft, and over a second sprocket wheel 71 mounted on the operating shaft. The sprocket wheel 71 is preferably located intermediate the ends of the operating shaft 55. At one end this shaft carries a fly wheel 72. At its other end it carries a crank 73 for actuating the awl.

As shown, a crank shaft 74 is mounted upon the head 52, as by being journaled in a bracket lug 75 which is formed integral therewith. Two cranks 76, 77, are mounted upon the opposite ends of the crank shaft 74. One of these cranks, as 77, is connected with the crank 73 as by a link 78. A link 79 serves for connecting the other crank, as 76, with a collar 80 which is fixed upon the awl 30. As the point of connection between the link 79 and crank 76 is not far removed from the axis of pivotal movement of the frame 58, the swinging of the frame 58 does not interfere with the vertical reciprocation of the awl.

A cam 81, which is fixed upon the operating shaft 55 adjacent the fly wheel 72, serves for swinging the frame 58 to give the required lateral movement to the awl for feeding the work. As shown, movement is transmitted from the cam 81 to the swinging frame 58 by a bell crank lever 82. This bell crank lever is pivotally supported upon the head 52 at 83 (Fig. 1). One arm of the bell crank lever carries a stud 84 for engagement with the cam 81. The other arm of the bell crank lever is provided with a slot 85 for receiving a stud 86. The stud 86 is adjustably fixed in a crank-arm 87, which swings with the frame 58. By shifting the position of the stud 86 upon the crank arm 87

87, the amount of movement imparted to the frame 58 at each movement of the bell crank lever 82 may be varied. This serves for adjusting the length of the stitch.

5 The thread guide or looper 60 is actuated through a cam 88. This cam is mounted on the operating shaft 55 between the cam 81 and the sprocket wheel 71. It takes the form of a disk, having a peripheral cam groove 89. An upright lever 90, which extends downwardly through the head 52 and is pivotally supported upon a bracket arm 91 carried thereby, is provided with a stud 92 for running in the cam groove 89. A 10 link 93 connects the lower end of the lever 90 with a horizontally movable lever 94. The lever 94 is pivotally secured against the under side of the head 52, as by a screw-bolt 95. Preferably one end, as 96, of the lever 20 95 is downwardly offset. This downwardly offset end of the lever is connected with the thread guide or looper 60, for oscillating the same, by a link 97.

A cam 98, which is fixed upon the operating shaft 55 adjacent the sprocket wheel 71, serves for raising the presser foot 57. A lever 99 serves for communicating motion from this cam to the presser foot. This lever is pivotally supported intermediate its 30 ends, as between bracket lugs 100 which rise from the upper side of the head 52. One end of the lever 99 is upwardly turned, and is equipped with an anti-friction roller 101 for engaging the cam 98. The other end of 35 the lever 99 extends beneath a lug 102, which projects laterally from a collar 103 fixed upon the stem of the presser foot 57. A spring 104, coiled about the stem of the presser foot and reacting between the under 40 side of the head 52 and a second collar 105 which is mounted upon the stem of the presser foot, serves for depressing the presser foot and holding the anti-friction roller 101 in contact with the cam 98.

45 When the work has been fitted over the support 19 or 20, the usual form of chain-stitch seam may be produced by operating the several parts of the machine through the drive shaft 14. The slender form of 50 the work support, together with the pointed form of anvil block 28 and horizontal off-set in the work support, permit the stitching to be done at any part of the work, as at the corners of a suit-case or traveling bag, or at 55 the bottom of a golf bag. The tilting of the work support, as 19, to the position indicated by dotted lines in Fig. 1, facilitates the application of the work to the work support. If, for example, the work to be done 60 is that of forming a seam at the bottom of a golf bag, the work support, as 19, will be swung forwardly and the body of the bag slipped over the support to bring the pointed anvil block 28 in contact with the bottom 65 of the bag upon the inside. If now the

work support, as 19, be returned to the upright position, a seam may be formed at any part of the bottom of the bag.

I claim as my invention—

1. In a leather sewing machine, in combination, a tubular work support having upright end portions and a horizontal intermediate portion, a needle operating through the higher end of the work support, a head located above the higher end of the work support, stitch-forming elements mounted on the said head and co-operating with the said needle to form a seam, and a driving mechanism for operating the said stitch-forming elements and needle including a lever extending through the bore of the said horizontal intermediate portion of the tubular work support and fulcrumed therein intermediate its ends and plungers extending through the bore of the upright end portions of the tubular work support and connected with the opposite ends of the said lever and one of said plungers being connected with the needle. 70 75 80 85

2. In a leather sewing machine, in combination, a downwardly facing work head including a looper, awl and presser foot, an upwardly facing tubular work support mounted for movement into and out of register with the said work head, a needle operating through the higher end of the work support, and means for driving the said several operative parts including a plunger connected with the needle, said plunger being mounted within the bore of 90 95 100 the tubular work support and movable therewith.

3. In a leather sewing machine, in combination, a tilting tubular post, a needle operating through the higher end of the post, a head fixed in position above the post, stitch forming elements mounted upon said head and co-operating with the needle to form a seam when the tilting post is upright, and means for driving the said several operative parts including a plunger connected with the needle, said plunger being mounted within the bore of the tubular post and movable therewith during the tilting of the post. 105 110 115

4. In a leather sewing machine, in combination, a tilting tubular post, a needle operating through the higher end of the post, a head fixed in position above the post, stitch forming elements mounted upon said head and co-operating with the needle to form a seam when the tilting post is upright, means for driving the said several operative parts including a plunger connected with the needle, said plunger being mounted within the bore of the tubular post and movable therewith during the tilting of the post, and a latch for securing the post in upright position. 120 125

5. In a leather sewing machine, in combi- 130

nation, an upright tubular work support which is laterally offset intermediate its ends, the two end portions of said support being parallel, a needle operating through the higher end of the work support, a head located above the higher end of the work support, stitch forming elements mounted on the said head and coöperating with the said needle to form a seam, a drive shaft, 10 mechanism connecting the drive shaft and the said stitch forming elements and mechanism connecting the drive shaft and the said needle, the last named mechanism being operable through the bore of the two parallel 15 end portions and of the laterally offset intermediate portion of the tubular work support.

6. In a leather sewing machine, in combination, a normally upright tilting tubular work support which is laterally offset intermediate its ends, the two end portions of said support being parallel, a needle operating through the higher end of the work support, a head located above the higher end of 20 the work support, stitch forming elements mounted on the head and coöperating with the said needle to form a seam, a drive shaft,

mechanism connecting the drive shaft and the said stitch forming elements and mechanism connecting the drive shaft and the 30 said needle, the last named mechanism being operable through the bore of the two parallel end portions and of the laterally offset intermediate portion of the tubular work support.

7. In a leather sewing machine, in combination, a head, a tilting work supporting post, the tilting of the post serving to permit movement of the post between positions in which the higher end of the post registers 40 with the head and is spaced apart from the head for receiving the work, respectively, and a plurality of stitch forming elements, a part of said elements being carried by the head, a part of said elements being carried 45 by the tilting work supporting post and all of said elements coöperating to form a seam when the higher end of the post registers with the head.

OTTO E. HOFFMAN.
